UNITED STATES PATENT OFFICE.

ROBERT JULIUS PETERSEN, OF BIRMINGHAM, ENGLAND.

DEVICE FOR LOADING MAGAZINE-RIFLES.

1,088,925.

Specification of Letters Patent.

Patented Mar. 3, 1914.

Application filed June 12, 1913. Serial No. 773,341.

To all whom it may concern:

Be it known that I, ROBERT JULIUS PETERSEN, subject of the King of Great Britain, residing at Lench street, Birmingham, in the county of Warwick, England, have invented a new and useful Device for Loading Magazine-Rifles; and I do hereby declare the following to be a full, clear, and exact description of the same.

10 My invention comprises a loading device for magazine rifles, particularly Winchester rifles; and has for its object to provide a simple and effective means whereby a magazine rifle may be charged or loaded with a full supply of cartridges at one operation.

In a Winchester rifle a magazine is provided which contains the cartridges disposed end to end or in alignment with each other, such cartridges being held up to their feeding position by a spring plunger. The usual method of loading or charging such a rifle is by inserting each of the cartridges separately through a side opening, but this is a lengthy and tedious proceeding particularly 25 when the rifle is being used for show purposes; and in accordance with the present invention a full charge of cartridges is supplied to the magazine at one operation.

The loading apparatus includes a tubular member adapted to receive six, twelve or any other suitable number of cartridges inserted endwise into the tube; being provided with a stop or abutment which is released when the tube is placed in alignment with 35 the magazine, allowing the whole of the cartridges in the tube to pass endwise into the said magazine.

The loading device may be in the form of a simple tube or there may be a plurality of 40 these tubes arranged in a stand.

Referring to the drawings:—Figure 1, illustrates one form of the invention in which the tube is provided with a pair of stops. Fig. 2, is an end view of same. Fig. 45 3, is a longitudinal section. Fig. 4, illustrates a modified form of the invention in which the tube is only provided with one stop. Fig. 5, illustrates at rotary stand fitted with a plurality of tubes. Fig. 6, is 50 a detail section of one form of the stop employed in connection with the rotary stand.

In carrying my invention into practice as illustrated upon the accompanying drawings at Figs. 1-3 there is a tubular member 55 1 provided with an enlargement or enlarged bore 2 at its one end, the opposite end of

this tube being open to receive the cartridges this end being closed by a cap marked 3 the position of the cartridges being indicated by the dotted lines in Fig. 3.

The part 2 has a slot or opening 4 through which projects the stop. This stop is formed from sheet metal including a longitudinal spring portion 5 a pair of arms 6 which are bent to embrace the tube and to anchor the spring part 5 thereto, while at the opposite end the stop includes a part 7 projecting into the interior of the tube in a direction at right angles to the length of the tube, the extremity of the stop being in the form of an inclined part 8 so arranged that when the magazine tube of the rifle is pushed into the enlarged bore 2 it engages the incline 8 forcing it outwardly to release the cartridges which thus fall down into the magazine. The stop, spring, and arms may be conveniently formed from a single blank of sheet metal. These charging tubes are intended to supply a definite number of cartridges at a time to the rifle, say six but the device illustrated at Figs. 1-3 has a greater capacity than this number. It is therefore provided with a second stop at a distance from the first stop corresponding with the length of six cartridges, this second stop comprising a longitudinal member 9 secured to the tube by arms 10 and having a projection 11 passing through an opening in the tube so as to prevent passage of the cartridges when the projection is in its normal position, while in addition it has a fulcrum portion 12 and a thumb piece 13; all so arranged that when the thumb piece is pressed in, the part 11 is drawn outwardly to allow the cartridges above the part 11 to fall to the lower part of the charging tube.

Thus after six cartridges have been transferred to the magazine the stop 11 is operated which admits another supply of cartridges to the lower portion of the tube, or by operating this stop 11 the user may insure the correct number of cartridges being between the two stops.

A similar form of the apparatus is shown in Fig. 4 but in this case the total length of the tube is such as to receive only the number of cartridges which it is desired to pass to the magazine at one operation and in this case only the one stop is used.

At Figs. 5 and 6 the charging device is shown arranged as a rotary stand including two disks 14 rotatably disposed around a

central axis or spindle 15, these disks carrying a plurality of charging tubes of somewhat similar form to that shown in Figs. 1-3 having a similar stop at the lower end 5 but being open at the upper end and provided with a trumpet or bell mouth 16 for facilitating the insertion of the cartridges. In this case the second stop is of slightly different form consisting only of a single 10 pivoted lever 17 held to the tube by a clip 18 and having its extremity 20 bent at right angles to pass through an opening in the tube to form a stop for the cartridges so arranged that when the upper end of the lever 15 is pressed inwardly the end 20 moves outwardly to release the cartridges. Each of the tubes may be of a considerable length 20 adapted to receive a large number of cartridges and the rifle may be charged directly by inserting the magazine tube of the rifle in the enlarged bore 2 of the tubes carried by the stand, or the arrangement shown in Fig. 5 may be used only as a cartridge store from which the cartridges may be transferred to 25 an arrangement such as that shown in Fig. 4 by inserting the upper end of the tube shown in Fig. 4 into the enlarged bore 2 of the tubes carried by the stand, the cartridges being subsequently transferred to 30 the rifle in manner previously explained.

The tubes are provided with longitudinal slots 21 which allow the user to readily see the quantity of cartridges which are in the tube.

35. Claims:

1. In a device for loading rifles, the combination of a tubular member having a bore adapted to contain a plurality of cartridges placed end to end therein; an extension on 40 said member co-axial therewith and having a bore larger than the bore of said member, said enlarged bore corresponding with and being adapted to receive the extremity of a magazine tube of a rifle, the junction between the enlarged bore and the tubular member being in the form of a shoulder; a cartridge-retaining stop located in said enlarged bore and having its retaining portion so disposed as to retain the cartridges within 45 the aforesaid tubular member and having also an inclined extremity facing toward the open end of the enlarged bore and a spring arm carrying said retaining stop, so arranged that the magazine tube of the rifle 50 when inserted into said enlarged bore of the said extension against the said inclined extremity automatically presses the retaining stop outwardly, releasing the cartridges and permitting them to fall by gravity one behind the other into the open end of the 55 magazine of the rifle; for the purpose specified and substantially as set forth.

2. In a device for loading rifles, the combination of a tubular member adapted to 60 contain a plurality of cartridges placed end

to end therein and having an enlarged bore at one end; a spring actuated stop located adjacent to said enlarged bore and normally projecting within the tubular member so as to retain the cartridges in said tubular member but adapted when another tubular member is inserted in said enlarged bore to automatically release the cartridges; and a second stop fixed to the tubular member, located at a distance from the first stop and normally preventing passage of the cartridges to the first stop but permitting a predetermined quantity to pass at will; for the purpose specified and substantially as set forth. 70

3. In a device for loading rifles, the combination of a tubular member adapted to contain a plurality of cartridges placed end to end therein and having an enlarged bore at one end; a stop for normally retaining the cartridges therein embodying a laterally projecting abutment, an inclined extremity, a spring limb, and a pair of arms at one end of said spring which embrace the tubular member and secure the strip in position; and a second stop fixed to the tubular member, located at a distance from the first stop and normally preventing passage of the cartridges to the first stop but permitting a predetermined quantity to pass at will; for the purpose specified and substantially as set forth. 80

4. In a device for loading rifles, the combination of a tubular member adapted to contain a plurality of cartridges placed end to end therein; a spring actuated stop normally projecting within the tubular member so as to retain the cartridges therein but adapted to be retracted to release the cartridges; and a second stop formed from a strip of spring metal having a pair of arms 100 at its one extremity which embrace the tubular member and secure the stop thereto, an inwardly projecting lug abutting against the exterior of the tube to act as a fulcrum and a second inwardly projecting member 110 normally extending through an opening in the tube but adapted to recede when the extremity of the stop is pressed inwardly; for the purpose specified and substantially as set forth. 115

5. In a device for loading rifles, the combination of a tubular member adapted to contain a plurality of cartridges placed end to end therein and having an enlarged bore at one end; a spring actuated stop located adjacent to said enlarged bore and normally projecting within the tubular member so as to retain the cartridges in said tubular member, but adapted when another tubular member is inserted in said enlarged bore to automatically release the cartridges; and a second stop formed from a strip of spring metal having a pair of arms at its one extremity which embrace the tubular member and secure the stop thereto, an inwardly project- 120 125 130

ing lug abutting against the exterior of the tube to act as a fulcrum and a second inwardly projecting member normally extending through an opening in the tube but adapted to recede when the extremity of the stop is pressed inwardly; for the purpose specified and substantially as set forth.

6. In a device for loading rifles, the combination of a tubular member adapted to contain a plurality of cartridges placed end to end therein and having an enlarged bore at one end; a stop for normally retaining the cartridges therein embodying a laterally projecting abutment, an inclined extremity, a spring limb and a pair of arms at one end of said spring which embrace the tubular member and secure the stop in position; and a second stop formed from a strip of spring

metal having a pair of arms at its one extremity which embrace the tubular member and secure the stop thereto, an inwardly projecting lug abutting against the exterior of the tube to act as a fulcrum, and a second inwardly projecting member normally extending through an opening in the tube but adapted to recede when the extremity of the stop is pressed inwardly; for the purpose specified and substantially as set forth.

In testimony whereof, I have signed my name to this specification in the presence of two subscribing witnesses.

ROBERT JULIUS PETERSEN.
